UNITED STATES PATENT OFFICE.

CHARLES H. OSLUND, OF WORCESTER, MASSACHUSETTS, ASSIGNOR TO THE O & J MACHINE COMPANY, A CORPORATION OF MASSACHUSETTS.

STRINGING-UP DEVICE FOR WIREDRAWING DRUMS.

Application filed May 22, 1922. Serial No. 562,601.

To all whom it may concern:

Be it known that I, CHARLES H. OSLUND, a citizen of the United States, residing at Worcester, in the county of Worcester and State of Massachusetts, have invented a new and useful Stringing-Up Device for Wire-drawing Drums, of which the following is a specification.

The principal objects of this invention are to provide a wire drawing block with means whereby the wire can be connected to the block and wound thereon by hand as many times as desired to draw it through the die before the block is positively connected with the power.

Further objects and advantages of the invention will appear hereinafter.

Reference is to be had to the accompanying drawings, in which—

Fig. 1 is a plan of a wire drawing drum constructed in accordance with this invention, and

Fig. 2 is a central sectional view of the same.

I have shown the invention as applied to a machine capable of drawing steel wire through three or more dies continuously.

When the wire is brought through the die to the first drum it, of course, starts in a slack condition. It has to be flattened to pass through the die and then has to be drawn through the die to produce an end long enough to fasten it to the drum. This is usually done by a tongs and chain device having a reciprocating or oscillating motion. This invention constitutes a substitution for the mechanism for producing that motion, the tongs and chain being used as before. I have departed from the

methods known to me and I provide a positive means of driving the drum at all times but arrange it so that the power operated means is readily disconnected from the drum. However, when disconnected the

drum can be operated positively by hand. It is so arranged that in drawing through the drum is operated by hand positively. The drum itself is used for the drawing through or stringing up operation. The wire is connected with the drum in the same way as it is usually connected with the os-

cillating device and in this way the operator can start the drum by hand as slowly as may be desired and avoid the troubles that have been encountered in the previous devices. When he gets enough wire drawn through the die he withdraws the hand operating device, or disconnects it, and the drum is operated by power positively at a normal constant speed. The invention can be applied to all the drums of the wire drawing bench although I have shown only one.

I have illustrated the invention as applied to a drawing-through drum 10 mounted to rotate on the bench 9. This drum has a flat bottom provided with a central hub 11 which is vertical ordinarily. Up through this hub extends a vertical positive driving shaft 12 projecting up from below from the gearing by which it is driven. This is arranged to support the drum which is centered on the hub. The top of this shaft 12 is squared off at 13 or otherwise formed of a non-circular shape. Fitting this part 13 so as to run with it positively is a hub 14 having an external rack 15 preferably in the form of ratchet teeth. This rack, therefore, rotates positively with the shaft 12 at all times although the drum 10 is capable of rotating independently of the shaft, that is, it is free thereon. The circular rack or gear 15 is fixed on the end of the shaft also, if desired, by a screw 16.

Extending up from the bottom of the drum 10 near the circumference is a boss 18 through which passes a vertical shaft 19 having keyed to it a handle 20 for oscillating it on its bearing in the boss 18. This handle has an integral arm 21 so as to constitute a bell crank. On this arm is an integral stud 22 which extends upwardly into an elongated slot 23 in a bell crank or double lever 24. This is mounted on a stud 25 and has a pawl 26 on the other end adapted to engage in the teeth of the rack 15. There is also a spring 27 which connects the inside of the drum with the handle 20 and holds it in either of its extreme positions as shown fully in dotted lines in Fig. 1. It, of course, permits it to be moved by operation of the handle to the other position. As the shaft 19 is mounted on the drum and as the rack 15

is positively driven by the driving shaft 12, the drum will be positively driven through these parts connected by the pawl 26 when the parts are in the full line position shown in Fig. 1.

On the bottom of the drum is a bevel gear 30. With this is adapted to mesh a bevel pinion 32 on a shaft 33. Fixed on the end of this shaft is a crank handle 35 and the shaft has a bearing 34 on the bench. This bevel gear 32 when turned by the crank 35 will rotate the drum 10 positively. When it is not desired to have the handle 35 rotated by the drum the whole device consisting of the parts 32, 33 and 35 may be drawn out because the largest part of the pinion 32 is smaller than the bearing 34. They can be taken entirely out or left part way out so as to bring the pinion 32 out of mesh with the gear 30.

The operation is as follows:—The short end of the wire W passing through the die D is connected to the drum in any desired way, as for example, by connecting it to a pair of tongs having a hook passing through a hole through the side of the drum. The handle 20 is turned to the dotted line position before the wire is connected so that the drum cannot be driven by the constantly rotating drive shaft 12. As soon as the wire is connected the stringing up device consisting of the elements 32, 33 and 35 is put in place as shown in the drawings. The handle 35 is rotated forwardly to turn the drum 10 and draw the wire through the die. When enough wire is drawn through the die to enable it to be attached to the drum the tongs and chain are disconnected, preferably, and the end of the wire connected to the drum in any of the usual ways. Then the handle 20 is swung over to the full line position in Fig. 1. Then, this handle 35 with its connected parts is withdrawn and laid to one side and the shaft 12 started. Then the drum will continue to rotate and draw the wire positively in the usual way. I do not claim herein anything shown and claimed in my copending application, Serial No. 477,814, filed June 15, 1921.

Although I have illustrated and described only a single form of the invention, I am aware of the fact that modifications can be made therein without departing from the scope of my invention as set forth in the claims. Therefore, I do not wish to be limited to all the details of construction herein shown and described but what I do claim is:—

1. In a stringing up device for a wire drawing machine, the combination with a driving shaft and a drum, of means within the drum for rotating the drum positively from the shaft, said means being movable to inoperative position, and a hand operated device outside the drum and at the side

thereof for rotating the drum positively independently of the driving shaft at any desired speed.

2. In a stringing up device for a wire drawing machine, the combination with a driving shaft and a drum, of means within the drum for rotating the drum positively from the shaft, said means being movable to inoperative position, a bearing on the bench of the machine located radially with respect to the drum, a shaft adapted to be moved into said bearing from the end thereof and having on one end means for rotating the drum positively and on the other end means for operating it by hand.

3. The combination with a wire drawing drum, of a driving shaft concentric therewith but relatively rotatable, a wheel fixed with respect to said shaft, a shaft mounted on said drum, a lever pivoted on the last named shaft, and means operated by the lever for connecting the drum with the wheel to rotate the drum positively therefrom, the lever being capable of being turned to two positions for connecting the drum or disconnecting it from the driving shaft.

4. The combination with a wire drawing drum, of a driving shaft, said shaft and drum being concentric therewith but relatively rotatable, a ratchet wheel fixed with respect to said shaft, a shaft paralleled with the driving shaft mounted on said drum, a lever pivoted on the last named shaft, one arm of said lever having a stud thereon, a pawl for engaging the teeth of the ratchet wheel having an arm provided with a slot in which said stud is located, whereby the lever can be turned to two positions for moving the pawl either into or out of engagement with the ratchet wheel and when in engagement the drum will be positively driven by the driving shaft through the ratchet wheel, pawl, arm, lever and shaft.

5. The combination with a wire drawing drum, of a driving shaft, said shaft and drum being concentric but relatively rotatable, a ratchet wheel fixed with respect to said shaft, a shaft paralleled with the driving shaft mounted on said drum, a lever pivoted on the last named shaft, one arm of said lever having a stud thereon, a pawl for engaging the teeth of the ratchet wheel having an arm provided with a slot in which said stud is located, and a spring connecting the circumference of the drum with said lever and located in position to hold the lever yieldingly in each of its extreme positions, in one of which the pawl is in engagement with the ratchet wheel, and in the other of which it is free from it.

6. In a wire drawing machine, the combination with a drum for receiving wire on its surface, of a driving shaft on which

the drum is centered and relatively rotatable, a toothed wheel fixed to the shaft, a shaft parallel with the driving shaft located in the drum, means on the second shaft for connecting the toothed wheel with the drum to drive the drum positively therefrom, said drum having a gear thereon concentric with

the driving shaft, a removable shaft having a pinion adapted to mesh with said gear, and a crank for rotating it.

10

In testimony whereof I have hereunto affixed my signature.

CHARLES H. OSLUND.
